UNITED STATES PATENT OFFICE.

ALBERT A. SANBORN, OF NEWARK, NEW JERSEY, ASSIGNOR, BY DIRECT AND MESNE ASSIGNMENTS, TO THE CELLULOID MANUFACTURING COMPANY, OF NEW YORK, N. Y.

COLLAR OR CUFF OF CELLULOID.

SPECIFICATION forming part of Letters Patent No. 288,955, dated November 20, 1883.

Application filed September 19, 1881. (No model.)

To all whom it may concern:

Be it known that I, ALBERT A. SANBORN, of Newark, in the county of Essex and State of New Jersey, have invented a new and useful improvement in the manufacture of collars or cuffs of celluloid or similar plastic material with a hem, of which the following is a specification.

My invention relates to collars and cuffs made from celluloid or other pyroxyline material, with a hem formed by a turned-over edge of the celluloid, &c., giving strength to the article made from this material alone.

Figure 1 is a plan; Figs. 2 and 3, cross-sections on line $\alpha\alpha$ on Fig. 1.

The face portion A has the edges B turned over on the back of itself and cemented down,

making a hem, and a back, C, of the same or similar material, may be cemented onto the whole, covering and protecting the hem; but usually the article will be made without the back or lining C, simply the hem turned over and cemented down.

I claim—

A collar or cuff made of celluloid or other pyroxyline material, from a single thickness of the material, having the edges turned over onto itself to form a hem, substantially as specified.

ALBERT A. SANBORN.
